UNITED STATES PATENT OFFICE.

JOHN BARNITE, OF ALDEN, IOWA.

HOG-OILER.

1,291,367.

Specification of Letters Patent.

Patented Jan. 14, 1919.

Application filed July 1, 1918. Serial No. 242,802.

To all whom it may concern:

Be it known that I, JOHN BARNITE, a citizen of the United States, residing at Alden, in the county of Hardin and State of Iowa, have invented certain new and useful Improvements in Hog-Oilers, of which the following is a specification.

This invention has relation to hog oilers, and the nature and objects thereof will be readily apparent to those skilled in the art to which this invention appertains in the light of the following explanation of the accompanying drawings, illustrating what I now believe to be the preferred embodiment, or mechanical expression of my invention, from among other forms and arrangements within the spirit of the invention, or the scope of the appended claims.

However, an object of the invention is to provide, improvements in hog oilers of the type embodying a rotatable member against which the animal rubs itself, my improvement comprising means of a novel character for supplying oil or other fluid to the roller. Another object of the invention is to provide a hog oiler of the character above set forth embodying an oil reservoir, a conduit extending from said reservoir to the roller, and means operable during rotation of the roller to deliver a predetermined quantity of oil to the conduit.

A still further object of the invention is to provide a hog oiler of the character above set forth embodying a reservoir of the vacuum feed type for the purpose of maintaining a constant level in a well, and means for periodically removing predetermined quantities of oil from the well for supplying the same to the roller during rotation thereof.

A further object of the invention is to provide in a hog oiling apparatus, having the characteristics above set forth, means whereby the predetermined quantities of oil supplied to the roller may be varied at will.

In addition to the foregoing my invention comprehends improvements in the details of construction and arrangement of the correlative parts to be hereinafter more fully described and particularly set forth in the appended claims.

In the accompanying drawings in which similar and corresponding parts are designated by the same characters of reference

throughout the several views in which they appear:

Figure 1, is a view in vertical section of a hog oiling apparatus constructed in accordance with my invention.

Fig. 2, is a fragmentary view in front elevation of the upper portion thereof.

Fig. 3, is a detail view in horizontal section taken on the line 3—3 of Fig. 1.

Fig. 4, is a fragmentary view in detail illustrating a socket in the oil distributing wheel and

Fig. 5, is a transverse section taken on the line 5—5 of Fig. 1.

With reference to the drawings, 10 indicates a foot or base member consisting of a plate 11 preferably triangular in configuration having an enlargement 12 mounted upon the upper surface thereof, said enlargement extending upwardly and at an angle and having formed therein a socket 13 in which the lower end of a rod 14 extends. Suitable means is provided for anchoring the rod in place. Owing to the direction of the inclination of the socket it will be noted that the rod 14 is disposed at an angle. Mounted upon the upper end of the rod 14 is a circular can 15 formed at its bottom portion with semi-circular well 16 having a downwardly extending enlargement 17 formed exteriorly thereof and provided with a socket to receive the upper end of a rod 14. A set screw 18 enters the enlargement to engage the rod to secure the can. Surrounding the rod 14 is a sleeve 19 adapted to rotate and encircling the sleeve is a covering 20 of fabric secured in place by means of a strand of wire 21 wound spirally thereabout. Secured to the upper end of the sleeve 19 is a funnel-shaped member 22 designed to serve conjunctively as a funnel and an actuating means for the oil distributor in a manner to be presently noted. The surface of the sleeve 19 is formed with a plurality of longitudinally extending grooves 23 of varying lengths all beginning at the upper end of the sleeve where by the oil, when fed into the hopper 22 may enter the groove and thence flow down the sleeve supplying oil to the fabric covering the sleeve. It will be noted that the outer rim of the hopper member 22 is serrated as 24. Located within the well 16 is an oil

distributing wheel 25, the same being mounted upon the shaft 26 is disposed horizontally and mounted in bearings 27 secured to the bottom of the can said shaft extending 5 through an opening in the side wall of the can to project exteriorly thereof as shown in Fig. 3. The wheel 25 is grooved peripherally as at 28, and the bottom of the groove is deepened by the provision of a plurality 10 of circumferentially spaced recesses 29. Each recess is internally threaded to receive a plug 30 having a kerf in its outer end whereby an instrument may be inserted in the recess to engage in the kerf and to rotate 15 the plug to thereby vary the depth and capacity of the pocket at will. A tube 31 enters an opening in the well, the inner end of the tube being located within the groove 28 of the oil distributing wheel engaging the 20 wheel at a point near the top level of the well 16. The other end of the tube depends into the hopper member 22 as shown in Fig. 1. Mounted upon the outer end of the shaft 26 is a ratchet wheel 32 which is engaged by a pawl 33 to prevent rearward 25 rotation thereof. A shaft 34 is journaled in bearings exteriorly of the can 15 and extends across the front face thereof, one end of the shaft 34 being bent at right angles 30 and formed with a spring extension 35 acting as a pawl to engage the ratchet wheel 32. The opposite end of the shaft 34 is bent at right angles to form a terminal 36 which engages the serrated edge 24 of the funnel 35 member 22. A coil spring 37 is provided, having one end secured to the terminal 36 and the other end to the enlargement 17 mentioned above whereby to retain the terminal 36 of the shaft in engagement with 40 the serrated edge of the funnel-shaped member. The inner surface of the can 15 is formed with inwardly extending lugs 38 to support a reservoir 39 which is of an airtight construction, and is formed with a depending tubular member 40 having its lower 45 end disposed in closely spaced relation to the bottom of the can 15, which member 40 also constitutes a filling opening of the reservoir. Apertured lugs 42 are also formed 50 exteriorly of the can to receive vertically extending rods 43 having their upper ends bent to engage the upper edge of the reservoir 39, and their lower ends formed with enlargements 44. Coil springs 45 are 55 circled about the rod and interposed between said head 44 and the lug 42 to urge the rods downward and consequently retain the reservoir in place.

In operation, as the animal contacts with 60 the cloth covered sleeve 19, the sleeve is rotated, and the oil saturated fabric acts to spread the oil over the skin of the animal. During rotation of the sleeve 19 thus produced, the terminal 36 will be rapidly oscillated by means of the serrated funnel 22

thereby causing the pawl 35 to rotate the ratchet wheel in a series of steps, rearward rotation being prevented by means of a pawl 33. Rotation of the ratchet wheel 32 is transmitted through the shaft 26 to the 70 groove wheel 25, and each pocket in said wheel receives a supply of oil when reaching a lowermost position so as to carry the oil over the top of the wheel and subsequently deliver the oil when the pockets 75 are inverted into the conduit 31, the same conveying the oil to the funnel 22 which causes the oil to enter the groove 23 of the sleeve 19 for distribution to all parts of the fabric covering the same. It will be 80 noted that the oil within the reservoir 39 may flow by gravity through the tubular member 40 and fill the well 16 until the level of the oil rises above the lower end of the tubular member 40 whereupon the further 85 supply of material from the reservoir will cease until the level again falls due to constant abstraction of the oil by means of distributing wheels. It will be noted that by 90 adjusting the threaded plugs 30, the capacity or depth of the pockets or recesses in the distributing wheel may be varied to deliver different determined quantities of oil to the cloth covered sleeve.

The foregoing description and the drawings have reference to what may be considered the preferred, or approved form of my invention. It is to be understood that I may make such changes in the construction and arrangement and combination of 100 parts, materials, dimensions, etc., as may prove expedient and fall within the scope of the appended claims.

Having thus described my invention what I claim as new and desire to secure by Letters Patent is:—

1. In a hog oiler, a rotatable member for contact with the animal, a reservoir, a rotatable dipping means in said reservoir, a shaft upon which said dipping means is mounted, a ratchet wheel mounted on said shaft, a pawl engaging the ratchet wheel, and means mounted on the rotatable member to engage the pawl to oscillate the same whereby to successively rotate the dipping means.

2. In a hog oiler, a rotatable member, a reservoir, a rotatable dipping means within the reservoir, a ratchet wheel rotatable with said dipping means, a conduit for conveying material from the dipping means to the rotatable member, a pawl engaging the ratchet, and a circular serrated member rotatable with said rotatable member to engage the pawl to rotate the dipping means 125 step by step.

3. In a hog oiler, a rotatable cloth covered sleeve, a funnel mounted at the upper end of the sleeve having its rim serrated, a reservoir, a dipping means mounted in the reser- 130

voir, a conduit for conveying material from the dipping means to the funnel, a ratchet wheel for rotating the dipping means, and a pawl engaged in the ratchet wheel and the serrations of the funnel whereby to successively rotate the dipping means during rotation of the sleeve.

4. A hog oiler comprising a base having a socket therein, a rod having one end mounted in the socket, a sleeve secured on the rod, a funnel rotatably mounted to the top of the sleeve, a reservoir secured to the upper end of the rod, a dipping wheel rotatably mounted in the reservoir, means for conveying liquid from the dipping wheel to the funnel on the sleeve, and means engaging the funnel for rotating the dipping wheel when the sleeve is rotated.

5. A hog oiler comprising a base having a socket therein, a rod having one end mounted in the socket, a sleeve rotatably

mounted on the rod and provided with a plurality of longitudinally extending grooves, a cloth covering secured to the sleeve over the grooves, a funnel having a serrated upper edge, secured on the top of the sleeve and communicating with the grooves in the sleeve, a reservoir secured on the upper end of the rod, a dipping wheel rotatably mounted in the reservoir, means for supplying liquid from the dipping wheel to the funnel, and means engaging the serrated edge of the funnel for rotating the dipping wheel when the wheel is rotated.

In testimony whereof I affix my signature in presence of two witnesses.

JOHN BARTHITE.
